APPARATUS FOR INTESTINAL IRRIGATIONS

Fernand François Dominique Suarez de Mendoza,
Paris, FranceApplication November 21, 1934, Serial No. 754,159
In France November 21, 1933

11 Claims. (Cl. 128—227)

The present invention has for its object an apparatus for intestinal irrigations.

This apparatus is characterized by a reservoir placed under pressure and a reservoir placed under vacuum, these reservoirs being interconnected by two distinct conduits constituting a closed circuit traversing, at one part, in one of the conduits an air compressor and an air reservoir regulating the pressure, and, at the other part, in the other conduit a distributing three way cock and a suction vessel for surveyance of the substances, an equilibrium of pressure being established in all points of the circuit and the three way cock permitting of putting the rectal probe 15 in communication, under a certain constant pressure or under a certain constant degree of vacuum, either with the reservoir under pressure or with the reservoir under vacuum, so as to irrigate the intestine and to aspire, as often as necessary the injected liquid serving as vehicle for the contents of the intestine.

Another characteristic of the apparatus resides in the provision of a device placed ahead of the three way cock in the conduit leading to the rectal probe and permitting of leading of a medicinal solution or of a vaccine-matter into the intestine.

Different other characteristics will be better understood in the course of the following description and by referring to the accompanying drawings which show:

Fig. 1 a view of the complete apparatus for the application of the treatment;

Fig. 2 the three way cock and the distributor 35 of medicinal solutions;

Fig. 3 the three way cock in section on the line 3—3 of Fig. 2;

Fig. 4 the aspirating inspection device in a transverse section;

Fig. 5 the same organ in section on the line 40 5—5 of Fig. 4;

Fig. 6 the outlet cock in a transverse section, and

Fig. 7 a view of the apparatuses grouped together.

The general installation comprises in the first place two receptacles 61 and 62 of a capacity of about eighteen to twenty litres each.

The two receptacles should be provided with 50 tight lids or covers.

The receptacle 61 could, without inconvenience, be of glass or metal, but the receptacle 62 should preferably be of glass to render visible the movements of the liquid which it contains.

55 The cover 62a of the receptacle 62 is always

made of metal and is secured by appropriate means which bear strongly on the edge of the receptacle with an intermediate air-tight joint.

The installation also comprises a pump 63 driven by an electric motor. This pump is connected by a tube 64 to the receptacle 61, on the one hand, and on the other hand by a tube 65 to a reservoir or tampon bottle 66.

The purpose of the pump is to create a vacuum of about 35 centimetres of mercury in the receptacle 61, whilst it should keep up a constant pressure in the receptacle 62. The regulation of this pressure is obtained by means of the tampon bottle which is provided with an adjustable control valve 68 fixing and maintaining the pressure at any desired value between 10 1 meter 50 centimeters and 3 meters.

The receptacle 61, or vacuum receptacle, is provided with a drain pipe 70 having a cock 71. This cock comprises one plug only, provided with two distinct channels 71a and 71b (Fig. 6). The body of the cock is connected by two ways 71c and 71d to the pipe 70 and by two other ways 71e and 71f to an air pipe 72 traversing the cover 61a and ending there.

The plug of the cock 71 is acted upon by a pedal 71g (Fig. 1) and is provided with a tail 71h acting, after a certain stroke, upon a pusher cock or the like 75a fitted in the conduit 75 traversing the cover 61a and admitting water under pressure into the receptacle 61.

The plug of the cock 71 is automatically brought back and on being acted upon with aid of the pedal 71g causes the following action in chronological order: 1, the opening of the conduit 72 admitting air into the receptacle 61, and 2. the opening of the emptying conduit 70, and finally 3. the opening of the cock 75a admitting washing water into the receptacle 61.

On letting loose the pedal 71g the same returns into its starting position after having closed the three ways in an order inverse to the one on opening.

To control the emptying of the receptacle 61, an electric indicating device is attached to said receptacle. This device can be one with a swimmer 73 controlling through the medium of a rigid rod 73a a tight interruptor 73b destined to close the circuit of a test lamp 74.

A level controlling gauge 76 is disposed on the cover 61a to indicate constantly the level of liquid in the receptacle.

On the other hand a regulator 77 keeps the degree of vacuum of the receptacle 61 constantly to 35 centimeters of mercury.

The tube 18 is led into the cover 61, and conveys into the receptacle the liquid which has been used for the treatment and which holds in suspension the materials which have been evacuated from the intestine.

A tube 19 extends into the receptacle 62 and is carried by the cover 62. To this tube is connected the piping 14 comprising a serpentine 14, and connected to the distributing elements.

10 On the other hand, the cover 62 is traversed by a sliding thermometer 80 permitting the temperature to be noted, of the liquid introduced into the receptacle 62, by an orifice 81 having a hermetic mouthpiece.

15 Finally on the cover is mounted a valve 82, mechanical or preferably mercury, of which the glass float 83 is of a form which will permit manipulation of the cover without the possibility of reversing the mercury. This valve puts 20 the receptacle 62 into communication with the atmosphere as soon as the liquid descends below a determined limit in the receptacle.

The pipe 14 is connected to one of the nozzles viz. to the nozzle 84a (Fig. 2) of a cock 84 with four 25 perpendicular ways. The nozzles 84c and 84d are inflected so as to join two vertical bottles 84a and 84c. These bottles are obturated at their upper part and communicate with each other by a pipe 84'.

30 The plug of the cock 84 is provided with three conduits 84g, 84h and 84i and can hence occupy three positions controllable outwardly by an index or by any other suitable means.

In the first position (intermediate position) the 35 conduit 84i establishes the communication between the ways 84a and 84b. In the extreme left position the conduit 84g connects the ways 84a and 84c, and the conduit 84h the ways 84d and 84b with each other. Finally in the extreme right 40 position the conduit 84g connects the ways 84c and 84b, and the conduit 84h the ways 84a and 84d with each other.

Into the nozzle 84b of the cock 84 is screwed the end 12a of a three way cock 12, this end being 45 provided with a screw neck 45a comprising an internal screw thread in which screws the glass receptacle 45.

In the screw neck 45a are formed two passages 45b and 45c opening into the receptacle. The passage 45b is surmounted by a tube 46 extending up into the receptacle.

This arrangement permits the flow of the liquid controlled by the cock 12 to be watched.

To the branch 12b of the cock is fixed the tube 55 11 leading to the receptacle under vacuum 61. The nozzle 12c receives a tube 15 carrying the rectal probe 7.

The plug 12a of the cock 12 is provided with a conduit 12c permitting the interconnection, either 60 of the tubes 14 and 15 or of the tubes 15 and 11 or, finally, of the tubes 14 and 11 (Fig. 1).

To enable the operator to place the plug 12a in the desired position the handle 86 controlling the said plug is provided with an index 85a 65 moving over a dial 86 carrying marks corresponding to the three possible positions of the plug of the cock.

To maintain the cock in these positions and to facilitate finding these positions, the cock plug has six recesses in which can lodge a ball 87 (Fig. 3), pushed by a spring 88, and adapted to mark anyone of the three above-mentioned positions, or the three intermediate positions of closure of the cock.

75 The tube 11 leads to the inspection vessel com-

prising a base 23' (Fig. 4) carrying a glass hood 10.

This hood is held on the base 23' by means of a closing ring 25' tightened by wing nuts 30' mounted on swinging screws 29'.

5 Joints 89 and 90 are intercalated between the base and the hood to assure the air-tightness of this latter.

The base 23' forms, at its centre, a cup pierced with a hole from which leads the tube 18. A cock 19' is mounted on this tube 18 and permits of starting or stopping the circulation of the liquid in this latter.

10 The base 23' is also traversed by three tubes: a tube 91 connected directly to the tube 11, a tube 92 connected to the tube 18, below the cock 19' and a tube 93 connected directly to the top of the receptacle 61.

The tube 91 is raised sufficiently high in the 15 hood and terminates in a bent over portion, to divert the liquid of the column 11 to the centre of the hood.

The tube 92 does not extend so high and is 20 curved back on itself to a point near the base 23' in order to form a siphon.

The tube 93 allows of an equilibrium of the 25 vacuum between the receptacle 61 and the hood 10 to be obtained.

At the centre of the hood, above its central 30 cup may be disposed the funnel filter 20, pierced with holes and permitting of withdrawal of some quantities of the solid materials contained in the liquid.

The base has two manometers 94 one for the 35 control of the suction and the other for the control of the compression.

The above described apparatus functions as follows:

The operator moves the four way cock 84 and the three way cock 12 so that they form a communication between the receptacle 62 and the probe 7 by the intermediary of the tubes 14 and 15 and the control member 45 in which the liquid can be seen circulating.

40 After this quantity of liquid has been injected the operator moves the cock 12 so that he forms a communication between the probe 7 and the receptacle 61, by the intermediary of the tubes 15 and 11, of the member 10 and the tube 18.

45 Under the effect of the vacuum reigning in the receptacle 61, the liquid diverted into the intestine is then drawn into this receptacle after passing through the recuperating member 10 at a speed twice and a half greater than the speed, at which it is introduced. The operator can allow the liquid arriving by the tube 11 and the column 91 to run directly into the cup of the base 23' and into the pipe 18, but if it interests him he can close the cock 19' and allow the liquid to rise in the recuperating vase 10. He can then exactly survey the aspect of the liquid evacuated and, at the same time, control the volume of this liquid which should be at least equal to the volume injected.

50 60 65 This method avoids stagnation of the liquid in the intestine treated.

The operator could likewise inject a vaccine or a medicinal solution by placing either the one or the other in the ampulla 84c. By closing 70 the plug of the cock 84 into its right position (Fig. 2), the operator diverts the current of liquid under pressure arriving through the pipe 14 and conduit 84g towards the ampulla 84c of which the air is driven out and exerts a pressure 75

on the solution contained in the ampulla 84. This solution is then forced across the conduit 84_h towards the three way cock 12 and therefrom to the probe 1. An obturating system, such as 5 a float 84' can be provided for preventing the passage of the propelling liquid into the ampulla 84, when empty.

If the operator desires to continue the injection he replaces the cock 84 to its position to the 10 right.

For emptying the ampulla 84, filled with the propelling water, the operator can put this ampulla after operation into communication with the three way cock 12 across the conduit 84_g, 15 viz, by turning the plug of the cock 84 to the left, and so admit suction water to the suction receptacle 61.

The operator could moreover dispose in the vase 10 the recuperating filter 20 and thus gather 20 a certain quantity of solid material for examination or analysis.

The vase 10 should be of sufficient size to contain the quantity of liquid injected at each operation.

If, by inadvertence, the cock 19' being closed, 25 the liquid rises in the vase 10 above the summit of the tube 92, siphonage will occur in this latter and the liquid will travel by this tube directly into the tube 18 behind the cock 19'. This prevents all passage of liquid into the tube 93.

The operator can, after having finished the treatment, proceed to clean the tubing and the vase 10, for which purpose he moves the cock 12 so as to place in communication the tube 14 with 35 the tube 11.

The vase 61 which will have received the whole 40 of the liquid evacuated and measured by means of the gauge 76, can be cleaned after emptying by means of water under pressure coming from the pipe 75.

All accident is also rendered impossible in connection with the compression. The regulator 68 allows any desired constant pressure to be maintained in the bottle 66.

The temperature of the liquid introduced into the receptacle 62 is verified by means of the thermometer 80.

The float 83 prevents compression in the receptacle 62 when the level of the liquid reaches 50 an extreme minimum; no injection of air into the intestine undergoing treatment can therefore occur.

From the time that the receptacle 61 starts to 55 receive the liquid, the signal lamp 74 lights and shows that the apparatus is functioning normally and that the cock 71 is properly closed.

The whole of the apparatus described above can advantageously be placed in a single portable 60 article of furniture 95 (Fig. 7).

For this purpose one could arrange the pump 63 in the base of the article and above the bottle regulating the pressure 66 and the receptacle 61.

Doors 95_a and 95_b when folded down allow of 65 seeing and reaching the various inspection and control organs placed in the article, and also form flaps which are very useful to the operator.

Exteriorly, the article supports at its upper part, 70 the receptacle 62 preferably of glass and the recuperating vase 10 mounted on a hollow column 96 adapted to receive the various supple pipes leading to the three way cock. This column 96 projects from the article in such manner as to place as close as possible to the operator the receptacle 62 and to bring also the three way 75

cock within the reach of the operator's hand above the operation table.

It is obvious that the pump 63 could be replaced by any other apparatus capable of creating a pressure and a depression simultaneously 5 in the two circuits of the apparatus described.

For example one could use for this purpose compressed gas cylinders or the compressed air piping existing in certain towns.

The pump could be operated by hand or by a 10 motor.

Finally the apparatus described above by way of simple example in no way limitative could receive modifications of form and detail without exceeding the scope of the invention.

It will moreover be understood that the apparatus could be used not only for successive injections and aspirations according to the method of the invention of alternatively operating the three way cock, but also for continuous injections with 20 a double flow probe without changing the position of said cock.

What I claim, is:

1. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock in said liquid transferring conduit, a probe connected to said three-way cock to be set by said cock into communication with either said liquid supply reservoir or said receiving reservoir as desired, an aspirating and inspection device located in the liquid transferring conduit at a place between said three-way cock and said receiving reservoir, and a funnel filter in said aspirating and inspection device for gathering a quantity 30 of the solids suspended in the liquid aspirated from the intestine.

2. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock 40 in said liquid transferring conduit, a probe connected to said three-way cock to be set by said cock into communication with either said liquid supply reservoir or said receiving reservoir as desired, an aspirating and inspection device located in the liquid transferring conduit at a place between said three-way cock and said receiving reservoir, and a funnel filter in said aspirating and inspection device for gathering a quantity 40 of the solids suspended in the liquid aspirated from the intestine.

2. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock 50 in said liquid transferring conduit, a probe connected to said three-way cock to be set by said cock into communication with either said liquid supply reservoir or said receiving reservoir as desired, and a distributor of vaccine or medicinal solution, preceding the three-way cock and comprising two ampullas attached to two vertical nozzles of a four-way cock connected with its other two nozzles to the receptacle under pressure and to the three-way cock, said ampullas being air-tight and being connected together by means of a tube passing through their covers, said four-way cock serving to permit using the liquid under pressure for chasing air from the first said ampulla and to act by this air under 55 pressure upon the medicinal solution contained in the second ampulla in order to expel this solution towards the three-way cock and the probe, to permit the injection of a medicament at any moment of the treatment without mixing it with the washing water.

3. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock 60 in said liquid transferring conduit, a probe connected to said three-way cock to be set by said cock into communication with either said liquid supply reservoir or said receiving reservoir as desired, and a distributor of vaccine or medicinal solution, preceding the three-way cock and comprising two ampullas attached to two vertical nozzles of a four-way cock connected with its other two nozzles to the receptacle under pressure and to the three-way cock, said ampullas being air-tight and being connected together by means of a tube passing through their covers, said four-way cock serving to permit using the liquid under pressure for chasing air from the first said ampulla and to act by this air under 65 pressure upon the medicinal solution contained in the second ampulla in order to expel this solution towards the three-way cock and the probe, to permit the injection of a medicament at any moment of the treatment without mixing it with the washing water.

- above the liquid levels therein, means in said second conduit for establishing a positive pressure within said supply reservoir and a negative pressure in said receiving reservoir, a three-way 5 cock in said liquid transferring conduit, a probe connected to said three-way cock to be set by said cock into communication with either said liquid supply reservoir or said receiving reservoir as desired, a distributor of vaccine or medicinal 10 solution, preceding the three-way cock and comprising two ampullas attached to two vertical nozzles of a four-way cock connected with its other two nozzles to the receptacle under pressure and to the three-way cock, said ampullas 15 being air-tight and being connected together by means of a tube passing through their covers, said four-way cock serving to permit using the liquid under pressure for chasing air from the first said ampulla and to act by this air under 20 pressure upon the medicinal solution contained in the second ampulla in order to expel this solution towards the three-way cock and the probe, to permit the injection of a medicament at any moment of the treatment without mixing 25 it with the washing water, and a visor disposed between the four-way cock and the three-way cock, to permit the control of the normal flow of the liquid conducted into the probe.
4. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive 30 pressure within said supply reservoir and a negative pressure in said receiving reservoir, a three-way cock in said liquid transferring conduit, and a probe connected to said three-way cock to be set by said cock into communication with either said liquid supply reservoir or said receiving reservoir as desired.
5. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock in said liquid transferring conduit, a probe connected to said three-way cock to be set by said cock into communication with either said liquid supply reservoir or said receiving reservoir as desired, a valve-controlled drain pipe 45 leading from said receiving reservoir, a wash-water supply pipe with a shut-off valve connected to said receiving reservoir, and means for opening the drain pipe valve and shut-off valve in order to flush said receiving reservoir.
6. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock in said liquid transferring conduit, a probe connected to said three-way cock to be set by said cock into communication with either said liquid supply reservoir or said receiving reservoir as desired, and an aspirating and inspection device located in the liquid transferring conduit at a place between said three-way cock 50 and said receiving reservoir.

7. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock in said liquid transferring conduit, a probe connected to said three-way cock to be set by said cock into communication with either said liquid supply reservoir or said receiving reservoir as desired, a valve-controlled drain pipe leading from said receiving reservoir, a wash-water supply pipe with a shut-off valve connected to said receiving reservoir, means for opening the drain pipe valve and shut-off valve in order to flush said receiving reservoir, and an aspirating and inspection device located in the liquid transferring conduit at a place between said three-way cock and said receiving reservoir.

8. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock in said liquid transferring conduit, a probe connected to said three-way cock to be set by said cock into communication with either said liquid supply reservoir or said receiving reservoir as desired, and a transparent inspection receptacle connected in the liquid transferring conduit at a place adjacent said three-way cock and between it and said liquid supply reservoir.

9. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock in said liquid transferring conduit, a probe connected to said three-way cock to be set by said cock into communication with either said liquid supply reservoir or said receiving reservoir as desired, an aspirating and inspection device located in the liquid transferring conduit at a place between said three-way cock and said receiving reservoir, and a transparent inspection receptacle connected in the liquid transferring conduit at a place adjacent said three-way cock and between it and said liquid supply reservoir.

10. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock in said liquid transferring conduit, a probe connected to said three-way cock to be set by said cock into communication with either said liquid supply reservoir or said receiving reservoir as desired, an aspirating and inspection device located in the liquid transferring conduit at a place between said three-way cock and said receiving reservoir, said aspirating and inspection device including a vase having a transparent hood, an inlet tube to receive liquid from said three-way cock and deliver it into said transparent hood.

an outlet tube from said hood communicating with said receiving reservoir for emptying said vase, a third tube connecting said vase to said second conduit at the negative pressure side thereof, and a fourth tube containing a shut-off cock connecting the vase with the outlet tube substantially as and for the purposes described.

11. In apparatus for intestinal irrigation, a liquid supply reservoir, a receiving reservoir, a liquid transferring conduit connecting said reservoirs, a second conduit connecting said reservoirs above the liquid levels therein, means in said second conduit for establishing a positive pressure within said supply reservoir and a negative pressure in said receiving reservoir, a three-way cock in said liquid transferring conduit, a probe connected to said three-way cock to be set by said cock into communication with either said liquid supply reservoir or said receiving reservoir

as desired, an aspirating and inspection device located in the liquid transferring conduit at a place between said three-way cock and said receiving reservoir, said aspirating and inspection device including a vase having a transparent hood, an inlet tube to receive liquid from said three-way cock and deliver it into said transparent hood, an outlet tube from said hood communicating with said receiving reservoir for emptying said vase, a third tube connecting said vase to said second conduit at the negative pressure side thereof, and a fourth tube containing a shut-off cock connecting the vase with the outlet tube, and a funnel filter located in said vase for gathering solids from the liquids passing through the vase.

FERNAND FRANCOIS DOMINIQUE
SUAREZ DE MENDOZA.
